TUBE EXPANDER

Frederick C. Naher, Scotia, N. Y.

Application January 8, 1932. Serial No. 585,459

2 Claims. (Cl. 153—82)

This invention relates to tools and particularly to an improved tool or device for expanding the ends of tubes which are extended through orifices in curved sheets. Tools of this character are commonly known as roller tube expanders. In the expansion of tubes in orifices of curved sheets, such as in drums, difficulty has been experienced in the tendency of the tool to disturb the position of the tube in the drum during the expanding operation. Further difficulty has been experienced with tools of this character where it is necessary to pass the tool through a hole of a smaller diameter than the inside diameter of the tube to be expanded in order to reach the tube, as is often the case when expanding tubes in drums or cylinders. An object of the present invention is to provide a tool which will efficiently expand a tube in a curved sheet, such as the side of a drum, which tool will be positioned by the end of the tube in which it is inserted, so there will be no tendency to disturb the position of the tube with relation to the drum, and which tool will be capable of entering a hole of smaller diameter than the inside diameter of the tube to be expanded.

The invention is illustrated in the accompanying drawing, wherein Figure 1 is a sectional view of a tube inserted in an orifice in a drum, the drum being indicated by broken lines, with a tool embodying the present invention, shown in operable position within the drum and extending into the tube; Fig. 2 is a longitudinal sectional view on an enlarged scale of the expander end of the tool, the expander pin being broken away at its ends, showing the pin in engaged position, taken on the line II—II of Fig. 3; Fig. 3 is a section on the line III—III of Fig. 2; Fig. 4 is a section on the line IV—IV of Fig. 2; and Fig. 5 is a view similar to Fig. 2 showing the pin in disengaged position.

A specific embodiment of the present invention is herein exemplified in connection with the expanding of a tube in a drum, so as to form a steam-tight connection, as shown in Figure 1. The drum 1 is provided with holes 2 and 3, and the tube 4 is inserted in the hole 2, the tube having a diameter only slightly less than the diameter of the hole 2. The tool of the present invention, indicated generally by the numeral 5, is adapted to be inserted into the drum through the hole 3 and to extend into the tube 4 for the expansion of the same. The hole 3 is approximately opposite to although, as shown, out of alignment with, the hole 2, and is of a diameter less than the diameter of the hole 2 and slightly less than the inside diameter of the tube. In usual practice the hole

3 is threaded and a threaded plug is provided for closing the same, which plug is removable for purposes of cleaning the boiler, repairing the tubes, etc. By using a small hole less metal need be cut out of the drum and a drum of greater strength is provided than would be if a larger hole were used. The inner end of the tube 4 extends slightly beyond the inner surface of the drum. It will be apparent that the tool must necessarily be of such size and construction as to permit it to pass through the hole 3.

In usual practice tube expanders are guided or positioned by the sheet into which the tube is being expanded, this method being satisfactory when rolling tubes into flat tube sheets. In the case of sheets having curved surfaces, however, such as cylinders or drums, such a method of guiding or positioning the tool against the concave inner surface of the drum cannot be satisfactorily used, and when it is attempted to guide or position the tool against the convex outer surface on the opposite side of the drum it has been found that there is a tendency to draw the tube further into the drum.

The tool of the present invention comprises a cylindrical housing 6, of a diameter less than the inner diameter of the tube, and having a longitudinal central opening 7 formed therein, through which opening is passed a tapered arbor 8. The arbor is provided with a straight end portion 9 of reduced diameter providing a shoulder 9a at its jointure to the tapered body portion. A washer 10 and nut 11 are secured at the extremity of the end portion 9, for preventing the arbor from being drawn out of the housing and allowing the tool to become disassembled and to engage the end of the housing for withdrawing the tool. Lateral openings 12 are symmetrically formed in the housing, and rollers 13 are disposed within the openings free for lateral movement therein relative to the longitudinal axis of the housing. The openings 12 are peened over at 14, at the surface of the housing to prevent the rollers from dropping out of the openings. The rollers are tapered to one-half the degree of the taper of the arbor, and are forced laterally outward as the tapered portion of the arbor is pushed forward adjacent thereto. It will be apparent that when the arbor is in disengaged or withdrawn position, the rollers may lie entirely within the housing, and when the arbor is pushed forward and the rollers are moved laterally outward, as aforesaid, their taper being one-half the amount of the taper of the arbor, the outer surface of the rollers will be straight and parallel.

with the axis of the tube and the housing of the tool. Each of the rollers is bevelled at the opposite ends of its roller surface as indicated at 13a, to such extent that when the roller is in its 5 outermost position the extreme edges of the bevels will be substantially flush with the surface of the housing. By virtue of the bevels, the housing may be inserted and withdrawn through the hole 3, and inserted into the tube 4, without 10 interference from the ends of the rollers, that is, when the housing is so inserted or withdrawn any roller which is in its outermost position will be moved inwardly by the slideable contacting of its bevels with the edge of the hole or tube past 15 which it is moved.

It has been the practice in expander devices to provide a collar on the housing adapted to bear against the inner wall of the drum to hold the device in position. Such collar, having a larger

20 diameter than the body of the housing, would therefore prevent the housing from passing through a hole through which the same could otherwise pass. The instant device provides an improved means for holding the tool in position, 25 relative to the tube to be expanded. In the housing 6, a plurality of slots 15 are formed between the openings 12. The slots are provided with slanting surfaces 16, 17 and 18 for purposes hereinafter described. Stops 19 are disposed within

30 the slots and pivotally connected to the housing by means of pins 20. The stops are provided with a plurality of relatively slanting surfaces 21, 22, 23, 23a, 24 and 25. To operate the expander the housing is first passed through the hole 3, with 35 the arbor in withdrawn or disengaged position and the stops inwardly swung and held in a position entirely within the housing, so as not to engage the edges of the hole 3. The straight portion 9 of the arbor, being of a reduced diameter,

40 as aforescribed, when the arbor is in withdrawn position there is sufficient room within the housing so that both the rollers and stops may be disposed entirely within the housing, as shown in Fig. 5. In this position, the surfaces 23a of the 45 stops will bear against the straight portion 9 of the arbor, or the parts may be proportioned to cause the wall 24 to engage the wall 18. The housing is turned to a position with one of the stops approximately at the bottom of the housing, 50 which stop will drop or swing downwardly and out of the housing and as the housing is moved into the tube, this stop will engage the end of the tube. It will be apparent that as the arbor is moved toward roller engaged position

55 which movement of the arbor must be begun before the housing has been moved to its innermost position with relation to the tube shown in Fig. 2, the shoulder 9a will bear against the surfaces 22 of the remaining stops, forcing these stops outwardly so that the surfaces 24 of all of the stops will engage the end of the tube, and all of the stops will be forced by the end of the tube to their outermost positions (see Figs. 1, 2 and 4), the stops being limited in their outward movement by 60

65 their surfaces 21 bearing against the surfaces 16 of the housing and their surfaces 23 bearing against the surfaces 17 of the housing.

In the roller engaged position as shown in Fig. 2, with the surfaces 24 of the stops bearing 70 against the end of the tube, the tool is held in a fixed position with relation to the tube independently of the drum 1 into which the tube is being expanded. When the arbor is being withdrawn to the disengaged position shown in Fig. 5, the surfaces 75 25 of the stops will engage the periphery

of the hole 3 and the stops will be pivotally swung into the position within the housing with their surfaces 23a bearing against the straight portion 9 of the arbor so that the tool can be drawn through the hole without interference from the stops. The arbor 8 is provided with a knuckle or universal joint 26 of any well known type, to permit its being rotated when, as in the instance illustrated in Fig. 1, the holes 2 and 3, in the drum are out of alignment with each other. The outer end of the arbor is squared at 27 to engage a motor or driving member (not shown) of any of the well known designs commonly used for such work. When the tool is in the position shown in Fig. 1 it is ready to operate and the forward movement of the arbor while the same is being rotated, exerts outward pressure on, and rotates, the rollers, and thereby effects the expansion of the tube within the hole of the drum.

The instant invention as aforescribed provides a tool which will efficiently expand a tube in a hole in a curved sheet, such as a drum, and which tool is positioned by the end of the tube. Any tendency to disturb the relative positions of the tube and the drum, is eliminated by this positioning. Further the invention provides a tool which is capable of insertion and removal through a hole of smaller diameter than the inner diameter of the tube being expanded.

While there has been hereinbefore described a specific embodiment of the present invention, it will be apparent to those skilled in the art, that many and various changes and modifications may be made without departing from the spirit of the invention and it will be understood that all and any such changes and modifications as fall within the scope of the appended claims are contemplated as a part of the present invention.

The invention claimed and desired to be secured by Letters Patent, is:

1. A tool for expanding a tubular object comprising a cylindrical housing having a plurality of spaced longitudinal openings formed therein, and a plurality of longitudinal openings formed in said housing out of alignment with the first said openings; rollers held in the first said openings free for lateral movement from positions within said housing to positions partially extending beyond said housing; stop members disposed in the second said openings pivotally connected to said housing and movable from positions within said housing to positions extending beyond said housing; and a rotatable longitudinally movable arbor extending through said housing arranged to engage said rollers for the exertion of lateral pressure thereon and to engage said stop members to move said members toward their outwardly extended positions.

2. A device for expanding the end portion of a tube circular in cross section extending into a drum through a hole oppositely disposed to a temporary circular opening, comprising a cylindrical housing having a front portion for insertion into said tube end portion and a rear portion adapted to project from said tube end portion; a tapered arbor carried by said housing centrally therein with its larger end to the rear of said housing; a plurality of tube expanding rollers carried by said housing front portion around said arbor to permit tube expanding transverse outward movement and return inward movement of said rollers; a flexible shaft secured at one of its ends to the rear end of said arbor for rotating and advancing said arbor to roll said rollers and to effect said roller outward movement for

expanding said tube end portion and for retracting said arbor to permit said roller inward movement whereby said housing may be inserted through said temporary opening and into said tube end portion; and a plurality of stops carried by said housing and arranged for outward and inward swinging movements to position outer portions of said stops outside of said housing in stopping positions by said outward movement and 10 to position said outer portions of said stops within said housing by said inward movement whereby said housing may be freely passed through said temporary opening, said stops being provided with inner portions for engagement with said arbor

5 whereby said outer portions are moved partially outward, by forward movement of said arbor relative to said housing, to tube end engaging positions and when said housing is partially within said tube end portion, upon further forward movement of said housing, the tube end, by engagement with said stops, will effect full outward positioning of said outer portions and said inner portions will be thereby moved away from said arbor to permit subsequent free relative forward movement of said arbor to effect said expansion by said rollers.
